DESIGN FOR A SPECTACLE FRAME

Alexander M. Rosenson, Washington, D. C.

Application September 23, 1948, Serial No. 148,717

Term of patent 14 years

(Cl. D57—1)

To all whom it may concern:

Be it known, that I, Alexander M. Rosenson, a citizen of the United States of America, residing at Washington, D. C., have invented a new, original, and ornamental Design for a Spectacle Frame, of which the following is a specification, reference being made to the accompanying drawing, forming a part thereof.

Figure 1 is a perspective view of a spectacle frame showing my new design.

Figure 2 is a top plan view thereof.

The dominant features of my design are the portions shown in full lines.

I claim:

The ornamental design for a spectacle frame, as shown and described.

ALEXANDER M. ROSENSON.
